DIELECTRIC HEATING UNIT

William H. Anderson, Elkridge, and Dean S. Shingler and Bruce Boyd, Baltimore, Md., assignors to Westinghouse Electric Corporation, East Pittsburgh, Pa., a corporation of Pennsylvania

Application March 1, 1949, Serial No. 78,902

11 Claims. (Cl. 219—47)

1

Our invention relates to small dielectric heating units of a type for dielectrically heating small objects.

Such a unit usually comprises an outer metal casing which contains the electronic tubes and high-frequency circuits which produce the high-frequency electrical energy needed for the dielectric heating. The high-frequency energy produced inside the casing is fed to two relatively insulated heating-electrodes carried by the top wall of the casing. The heating-electrodes are usually two small parallel plates which are arranged one above the other so that they provide a work-receiving space between them. The usual unit also comprises a two-member protective metallic cage which encloses or surrounds the heating-electrodes. One of the cage-members is hinged or otherwise raisable with respect to the other cage-member so that the cage can be readily opened and closed to provide easy access to the interior of the cage. Generally the raisable cage-member carries one of the heating-electrodes. At present, to the best of our knowledge, each self-contained unit of the type described is provided with a single cage only, and its capacity for heat-treating objects is correspondingly limited.

An object of our invention is to increase the capacity of a small self-contained dielectric heating unit of the type described by providing it with two independently-operable cages, each of which has a pair of heating-electrodes between which work can be dielectrically heat-treated.

A further object of our invention is to provide a way of modifying existing small dielectric heating units of the type described so as to provide them with a plurality of dielectric heating cages instead of the single cage at present provided. Consequently, the production of such units can be greatly increased at a small expense.

In the application of our invention to present models of dielectric heating units, we cut additional holes in the top wall of the casing of the unit and superimpose another wall which carries a pair of separated cages. Each cage contains its own pair of relatively insulated heating-electrodes; and the added structure includes a transfer-switch mechanism by means of which the single high-frequency supply inside the casing can be connected to and disconnected from the

2

heating-electrodes in the several cages in a predetermined manner. Consequently, either cage may be unloaded and reloaded while the other is closed and in its heating period. Additionally, the added structure contains a safety feature, operated by the switch mechanism, which prevents the application of high-frequency energy to the heating-electrodes of an opened cage.

In accordance with specific details of our invention, which we consider new and useful in and of themselves, a dielectric heating unit embodying our invention comprises a single switch-operating handle or operating member that passes through a wall of the casing of the unit. This handle selectively connects high-frequency energy to the heating-electrodes inside a cage of a two-cage unit, and at the same time grounds the heating-electrodes in the other cage of the unit.

Features, innovations and advantages of our invention, in addition to the foregoing, will be discernible from the following description of an embodiment thereof which is preferred at the present time. This description should be taken in conjunction with the accompanying drawings.

25 In the drawings, which are on varying scales:

Figure 1 is a perspective view of the upper part of a self-contained dielectric heating unit embodying our invention.

Fig. 2 is a partial vertical sectional view along the length of the unit;

Fig. 3 is a vertical sectional view substantially on the line III—III of Fig. 2;

Figs. 4 and 5 are horizontal sectional views substantially on the lines IV—IV and V—V, respectively, of Fig. 2;

Fig. 6 is a perspective view of a structurally-independent item of our invention, and

Fig. 7 is a schematic wiring diagram of the electrical connections utilizable in a unit embodying our invention.

While our invention can be incorporated in a separately designed unit, we prefer to incorporate it into existing designs and hence our invention is described in connection with the latter.

45 Referring more particularly to Figs. 1 and 3 of the drawings, a small portable dielectric heating unit comprises an outer metallic casing 2 consisting of suitably assembled walls. The walls comprise a front wall 4 with a slope panel section 6, opposite end walls 8 and 10, a back wall 12

and a horizontal upper wall 14 secured to the upright walls 4, 8, 10 and 12. The casing 2 contains the necessary electronic tubes, circuits and adjustable mechanism for generating energy at the desired high frequency. The generating equipment is supplied with commercially available power through a pair of conductors that can be connected to any suitable commercial power outlet. (In Fig. 7 the high-frequency generating parts are indicated collectively by a block 16. The generating equipment is of the tube-oscillator type. The low-voltage low-frequency conductors which supply energy to the generating equipment are indicated at 18 and 20. The high-frequency energizing circuit of the tube-oscillation generator comprises a grounded conductor 22 and an insulated conductor 24.)

In a conventional unit, the upper wall 14 would ordinarily be the outer top wall of the casing 2. For modifying such a conventional unit so that it embodies our invention, this wall 14 receives a structure which carries two metallic heating cages instead of the conventional single cage. To this end the wall 14 is provided with openings for the insulated heating-electrodes for the cages and for a switch-shaft of a transfer-switch that controls the energization of the heating-electrodes. Such holes are indicated in Fig. 2 as comprising a shaft-hole 25, and electrode-holes 27 and 29, one on each side of the shaft-hole 25. With the upper wall 14 perforated along the lines described, two sub-structures are secured to the casing, one below and one above the upper wall 14.

The lower sub-structure, shown more particularly in Figs. 5 and 6, comprises a framework 30 of insulating material. The framework 30 comprises a base plate 32, a securing plate 34 and posts 36 holding the plates together in parallel planes. The base plate 32 carries a double-throw transfer switch which comprises a movable contact in the form of a knife blade 38, and a pair of stationary switch contacts 40 and 42. The movable contact or knife blade 38 is centrally pivotally supported between the stationary contacts 40 and 42 by a pivot means on the base plate 32. The pivot means comprises a metal pivot 44. The knife blade 38 is twisted about its pivot through an insulating linkage which comprises links 46 and 48. The latter carries a socket 50 at its end. Operating means, described later, can turn the socket 50 about its own axis so that the linkage comprising the links 46 and 48 will twist the knife blade 38 one way or the other depending on the direction in which the socket 50 is turned; and this knife blade can be made to selectively engage the stationary contact 40 or the stationary contact 42. In Fig. 5 it is shown in a position engaging the contact 40 and out of engagement with contact 42; and in Fig. 6 it is shown in the reverse position.

The metal pivot 44 extends below the base plate 32 and is conductively directly connected to the insulated high-frequency energy supply conductor 24 inside the casing 2. Depending on its position, the movable contact or knife blade 38 completes a circuit from this insulated high-voltage high-frequency conductor 24 to either of the stationary contacts 40 and 42. Removably secured to the contacts 40 and 42 are ends of inductance coils 56 and 58 respectively.

The foregoing lower sub-structure is independently carried by the upper wall 14 by securing the top of its securing plate 34 to the under-

side of the upper wall. Consequently, the transfer switch mechanism and the inductance coils 56 and 58 are carried inside the casing. The remaining ends of the inductance coils 56 and 58 lie under the electrode-holes 27 and 29 respectively. These ends of the inductance coils 56 and 58 are removably attached to stiff upright conductors 60 and 62, respectively, of the upper sub-structure.

The upper sub-structure is secured to the outer side of the inner wall 14 and comprises a shallow dished metal member 64. This member 64 has a back wall 66, end walls 68 and 70, and a front wall 72. The end walls 68 and 70 are provided with flanges that rest on the end walls 8 and 10 of the casing 2. The member 64 has a generally flat upper or top wall 74 which is parallel to the upper wall 14 of the casing 2. Consequently, the upper wall 14 becomes an inner upper wall for the casing 2 and the upper wall 74 becomes an outer upper wall or top wall for the casing 2.

As shown in Fig. 2, top wall 74 of the upper sub-structure member 64 has a pair of openings 75 and 77 which are vertically in line with the holes 27 and 29, respectively, in the inner wall 14. On its upper side, the upper wall 74 carries a pair of short insulating tubes 80 and 82 of insulating material, these tubes being respectively in line with and about the holes 75 and 77. The tubes 80 and 82 respectively carry insulated heating-electrodes 84 and 86, the heating-electrodes being metal plates. The stiff conductors 60 and 62 are secured to the center of the heating-electrodes 84 and 86, respectively, and are air-insulated from the walls of the casing by the holes 27 and 75, and 29 and 77, respectively. Secured to the lower side of the upper wall 74 are short spacer tubes 88 and 90 which are coaxial with, but of larger diameter than, the holes 27 and 75, and 29 and 77, respectively. The stiff conductors 60 and 62 pass through the associated surrounding tubes and extend below the inner upper wall 14 so that the inductance coils 56 and 58, which they removably carry are suspended inside the casing with adequate air insulation completely around the conductors and the coils.

The upper top wall 74 of the upper sub-structure of the casing 2 carries two metal cages 92 and 94, with the cage 92 about the heating-electrode 84 and the cage 94 about the heating-electrode 86. The cage 92 comprises a lower cage-member 96 fixed to the top of the upper top wall 74 and an upper cage-member 98 hinged to the back end of the lower cage-member 96. The hinged member 98 carries a handle 100 so that it can be easily raised or lowered. Similarly, the cage 94 comprises a lower cage-member 102, a hinged upper cage-member 104 and a handle 106.

The hinged cage-members 98 and 104 carry heating-electrodes 110 and 112, respectively. These electrodes are solidly electrically grounded or connected to the metal casing 2 in any suitable way common to the art so that a high-frequency circuit is completed directly, or through the casing, to the other high-frequency supply conductor 22, shown in Fig. 7. Such grounding means for each of the electrodes 110 and 112 comprises a copper strap 116. When a cage 92 or 94 is closed, its heating-electrodes are spaced for dielectrically heating work therebetween, in a normal manner.

The bottom side of the upper top wall 74 of

the upper sub-structure also carries a means for controlling the electrical energization or potentials of the pairs of heating-electrodes 84 and 110, and 86 and 112. Referring more particularly to Figs. 1-4, this means comprises a manually operable switch-operating arm 120 for operating the transfer switch shown in Fig. 6, and for operating a selective grounding means for the insulated heating-electrodes 84 and 86. The arm 120 extends outwardly through a vertical hole 121 in the front wall 72 of the dished member 64, and is provided with a knob 122. The switch arm 120 can be oscillated to the right or left about a pivot 124. The arm 120 can be frictionally held or latched in either of its extreme positions.

The pivot 124 for the arm or handle 120 is rotatably carried in a frame secured to the underside of the upper top wall 74. This frame comprises a top plate 140, a bottom thrust plate 142 and pillars 144. The bottom plate 142 rests on the upper wall 14 and covers the hole 25 therein. The pivot 124 has a section of smaller diameter which passes downwardly below the plate 142 and fits into the socket 50 of the transfer switch mechanism shown in Fig. 6. A set screw 146, or the equivalent, ties the socket 50 to the pivot 124 so that both rotate together upon movement of the handle or arm 120.

As shown more clearly in Fig. 4, the arm 120 extends backwardly beyond the pivot 124 to provide a fork 150 to the legs of which are pivoted a pair of grounding bars or rods 152 and 154. The rod 152 moves through an enlarged hole 155 in the tube 88; and the rod 154 moves through a similar hole 157 in the tube 90; these holes being in the nature of guiding means directing a rod 152 or 154 against an insulated conductor 60 or 62, as the case may be. The rods 152 and 154 are metallic; and spring contacts 160 and 162, respectively, rub against them. These spring contacts 160 and 162 are solidly grounded to the casing 2 and serve as a further precaution for insuring that the rods are grounded at all times.

Also attached to the lower side of the top wall 74 of the upper sub-structure, on opposite sides of the arm member 120, are a pair of normally opened switches 164 and 166.

The operation of the equipment described is as follows: When the switch arm or handle 120 is moved to the left, with respect to Fig. 4, its rotatable pivot 124 to which the arm is rigidly secured, turns the socket 50 so that the linkage 46, 48 throws the knife blade 38 into engagement with the contact 40 and out of engagement with the contact 42, as shown in Fig. 5. The high-voltage high-frequency conductor 24 is thereby connected to the contact 40 so that high-frequency voltage is applied to the insulated heating-electrode 84 via the inductance coil 56 and the stiff conductor 60. When the arm or handle 120 is so moved to the left, it also moves the grounding rod 152 away from the stiff conductor 62 while moving the other grounding rod 154 into electrical engagement with the stiff conductor 62 that is attached to the insulated heating-electrode 86. Consequently, the insulated heating-electrode 86 will be at ground potential, and the cage 94 can be opened and work placed on this heating-electrode with safety.

After the cage 94 is closed, the arm 120 can be swung to the right. Such movement causes the knife blade 38 to disengage the contact 40 and

to engage the contact 42, as shown in Fig. 6. This movement also moves the rod 154 from the stiff conductor 62 and moves the rod 152 into engagement with the stiff conductor 60. Accordingly, the high-voltage high-frequency supply on the conductor 24 can pass to the insulated heating-electrode 86 via the pivot 44, knife blade 38, the stationary contact 42, the inductance coil 58 and the stiff insulated conductor 62. In the meantime, the heating-electrode 84 is grounded to the casing 2 via the stiff insulated conductor 60, the grounding rod 152 and the spring 160. Accordingly, the cage 92 can be opened, the work heated therein removed and new work placed on the heating-electrode 84. In this way the cages 92 and 94 are successively used; one of them heat-treating an object while an operator is reloading the other one.

The time interval consumed in switching is very small. On an integrated basis, the preferred embodiment of the invention permits an operator to use his time most advantageously, and permits the high-frequency generating equipment to be in operation almost continuously, being interrupted momentarily by the switching operation. The grounding of the unused insulated heating-electrode is important. At the high-frequencies used, the short path to ground prevents voltages which otherwise would appear on the unused heating-electrode and its connections through capacity coupling.

Fig. 7 shows utilizable electrical connections in a dielectric heating unit embodying our invention. Primarily power for the unit comes through the low voltage leads 18 and 20. The high-frequency generating equipment 16 comprises a transformer having a primary winding 196 which can receive power from the lines 18 and 20 through either of two branch circuits 188 and 190. The branch circuit 188 includes a switch 192 and the switch 166 in series, both of these switches being normally spring biased to open position. The branch circuit 190 includes a switch 194 and the switch 164 in series, both of these switches also being normally spring biased to open position. The switches 192 and 194 are attached to the cages 92 and 94, respectively. Each of the switches 192 and 194 move to open position when its associated cage is being opened and remains open as long as the cage is open. Fig. 7 schematically shows the cage member 93 of the cage 92 in closed position closing the switch 194 in the branch circuit 190. The cage 94 is shown open so that its cage-member 104 is away from the switch 192, and the latter is open.

When the arm or handle 120 is moved to the left, the knife blade or movable contact 38 engages the stationary contact 40. At the same time the arm or handle 120 closes the normally opened switch 164. Consequently, the branch circuit 196 is completed and high-frequency energy is available across the heating-electrodes 84 and 110 inside the closed cage 92. The branch circuit 188 for the cage 94 is opened at two places, at the arm controlled switch 166 and at the cage controlled switch 192. The insulated heating-electrode 86 of the cage 94 is grounded through the rod 154; and the other heating-electrode 112 of the cage 94 is grounded permanently.

When the cage 94 is closed and the handle 120 is moved to the right, the grounding rod 154 leaves the conductor 62 and the grounding rod 152 grounds the conductor 60. The tube oscillation generator equipment will now be energized

through the branch circuit 183 instead of the branch circuit 193, and high-frequency energy will be on the conductor 62.

While we have described our invention in its preferred form, it is obvious that the principles thereof can be embodied in a dielectric heating unit of a type described in ways other than that described as the preferred embodiment.

We claim as our invention:

1. A dielectric heating unit comprising a metallic casing adapted to contain high-frequency generating equipment, said casing having a pair of spaced generally horizontal upper walls, a plurality of metallic cages carried by said casing over said upper walls, each cage comprising separable cage-members, a heating-electrode inside each cage, a high-frequency supply comprising an insulated conductor inside said casing, below said upper walls, and circuits and switching means carried by and between said upper walls comprising horizontally operable switch means for selectively connecting said insulated conductor to one of said heating-electrodes.

2. A dielectric heating unit comprising a metallic casing adapted to contain high-frequency generating equipment, said casing having a pair of spaced generally horizontal upper walls, a plurality of metallic cages carried by the top one of said upper walls, each cage comprising separable cage-members, a heating-electrode inside each cage, a high-frequency supply comprising an insulated supply conductor inside said casing, below said upper walls, and circuits and switching means carried by and between said upper walls comprising operable switch means for connecting said insulated supply conductor to a selected one of said heating-electrodes, said switch means comprising grounding means between said spaced upper walls for grounding the remaining ones of said heating-electrodes, said switch means and said grounding means being operable by a control member which extends from said casing.

3. An invention including that of claim 2 but further characterized by said switch means comprising a separate stationary contact for each heating-electrode and movable contact-means operated by said control member and selectively engageable with said contacts, said contacts and contact-means being carried by the lower one of said upper walls, and said grounding means comprising movable grounding bars between said upper walls.

4. An addition for increasing the capacity of a dielectric heating unit comprising: a metallic wall means having a generally horizontal wall, a pair of metallic cages carried on the top of said wall, each of said cages comprising a pair of separable cage-members, an insulated heating-electrode in each cage, an insulated conductor extending downwardly from each heating-electrode, and passing through openings in said wall, movable bars selectively horizontally movable into engagement with said insulated conductors, guide means under said wall slidably carrying said bars, said bars being electrically connected so as to be at the potential of said wall, and gearing comprising a pivoted member and handle therefor for moving said bars.

5. An invention including that of claim 4 in further combination with a pair of stationary contacts inside said casing carried by said wall means, circuit means connecting said insulated conductors separately to said stationary contacts, a movable contact carried by said wall means se-

lectively engageable with said stationary contacts, interconnecting mechanical means on said movable contact adapted to be fastened to said pivoted member, whereby said handle can be used to move said movable contact and said bars simultaneously.

6. A dielectric heating unit of a type described comprising a metallic casing adapted to contain high-frequency generating equipment, said casing having a pair of spaced generally horizontal upper walls, a plurality of metallic cages carried by the top one of said upper walls, each cage comprising separable cage-members, an insulated heating-electrode inside each cage, an insulated conductor extending downwardly from each of said heating-electrodes and passing through holes in said walls, a pair of horizontally movable grounding bars movably supported between said walls, each bar being adapted to engage and disengage an associated one of said insulated conductors, a pair of stationary insulated contacts carried inside said casing under said walls, said contacts being horizontally separated, a connection from each of said contacts to one of said conductors, a contact-engaging switch-blade insulatedly supported under said walls, and pivoted to turn on a vertical axis into engagement with one or the other of said contacts, said generating equipment comprising an insulated supply conductor connected to said switch-blade, and handle means extending outside said casing, for operating said bars and switch-blade.

7. A high-frequency heating unit of a type described comprising a metallic casing adapted to contain high-frequency generating equipment providing an insulated supply conductor, said casing having wall means including a horizontally-extending top wall, a plurality of individual work-receiving members carried by said top wall, said top wall having a pair of openings below said work-receiving members, an insulated conductor extending downwardly from each of said work-receiving members and passing through one of said holes, horizontally movable grounding means, supporting means movably supporting said grounding means in said casing for selectively grounding said conductors, a pair of stationary insulated contacts supported in said casing, said contacts being horizontally displaced, a connection from each of said contacts to one of said conductors, a contact-engaging switch-blade, supporting means insulatedly pivotally supporting said switch-blade in said casing to turn on a vertical axis for selectively engaging said contacts, said switch-blade being connected to said supply conductor, and handle means extending outside said casing for operating said grounding means and switch-blade.

8. A high-frequency heating unit as defined in claim 7 but further characterized by said supporting means supporting said grounding means and switch-blade so that they are in adjacent levels immediately under said top wall.

9. A high-frequency heating unit as defined in claim 7 but further characterized by said supporting means comprising a supporting frame carried immediately under said top wall.

10. A high-frequency heating unit as defined in claim 7 but further characterized by said grounding means comprising horizontal bars located between a pair of said connection conductors and adapted to ground one or the other thereof.

11. A high-frequency heating unit as defined in claim 7 but further characterized by each of

said work-receiving members comprising an insulated dielectric heating-electrode, a cage about each of said heating-electrodes, and said connections comprising an inductance coil under the associated conductor.
